UNITED STATES PATENT OFFICE.

FREDERICK GEORGE GOLDSSTONE, OF PLUMSTEAD, LONDON, ENGLAND, ASSIGNOR TO JOSEPH FRANCIS BERNARD AND JOHN BRUCE BOLITHO, OF LONDON, ENGLAND.

ELECTRIC CONDENSER.

Application filed September 14, 1920. Serial No. 410,211.

To all whom it may concern:

Be it known that I, FREDERICK GEORGE GOLDSSTONE, a subject of the King of Great Britain and Ireland, and residing at 66 Dal-

5 line Road, Plumstead, London, S. E. 18, England, have invented certain new and useful Improvements in or Relating to Electric Condensers, of which the following is a specification.

10 This invention relates to electric condensers and more particularly to that type known as variable condensers in which alterations in the capacity of the condenser can be effected.

15 An object of the present invention is to provide a variable condenser which is more efficient and is better adapted to stand wear and tear than those at present in use, and which is simple and cheap to manufacture.

20 According to the invention the condenser comprises a plurality (comprising two series, positive and negative) of condenser surface elements each of which is in the nature of a shell or cup of suitable shape or 25 form such as is described or generated by the revolution or partial revolution of a line about an axis, the line meeting or cutting the axis at two points, and further comprises means for varying the capacity of the condenser elements.

30 For practical purposes a shell, described or generated by the partial revolution of a semicircle about its diameter, is probably the most suitable, but other forms may be 35 adopted; for example, such as are described or generated by the partial revolution about an axis of a semi-ellipse, parabola, hyperbola, or any suitable modification thereof, or by the revolution or partial revolution of a 40 bent line, or line including one or more angles, that is to say, such a line as, together with the axis of revolution, forms a rectangular or triangular figure in general outline.

45 Variability of the capacity of the condenser may be effected by adapting the positive and negative condenser elements to be rotatable relatively to one another about an axis common to both.

50 The variable condenser may consist of a negative set of shell or cup-like condenser surface elements and a positive set of shell or cup-like elements, with means for supporting both sets, and for enabling rotary relative movement about a common axis to

be effected, in order to vary the facing area of the condenser surface elements.

In the accompanying drawings which illustrate one convenient form of condenser according to the invention:

60 Figure 1 is an outside elevation of a condenser indicating the elements in the zero position.

Figure 2 is a sectional elevation in a plane at right angles to that in which the rims of the shell or cup elements lie.

Figure 3 is an elevation looking from right to left of Figure 2.

Figure 4 is a sectional plan taken on the lines XY of Figure 3 looking from beneath and shows the movable shell or cup elements 70 revolved into a position in which 50% of their condensing surface is out of use.

Figure 5 is a detail view of a suitable form of means for securing the stationary 75 cups in position.

In carrying the invention into effect according to one convenient mode, by way of example, a plate or frame 1 of brass or other metal has mounted upon it a set or series A 80 of (say positive) hemispherical shells or cups, (numbered 2 to 6), of a thin suitable metal. These cups 2 to 6 are of diminishing diameter and the peripheral edges or rims of the cups lie in the same plane, an air space 85 being provided between each cup and the next adjacent. The spacing of the cups is carried out so that the distance between each cup and the next corresponds with the usual practice in connection with the spacing of 90 condenser plates, or to suit the particular requirements for which the condenser is intended. While each shell or cup presents a circular rim or edge towards the plane of the brass plate or frame, only a portion (slightly 95 less than a semi-circle) of their rims is mounted in or upon the plate or frame.

For the purpose of mounting the shells or cups, a corresponding series or set of grooves are formed in the plate or frame in which a 100 portion (nearly a semicircle) of the rims or peripheries of the cups are fitted and secured. For the purpose of securing these cups two bars 6^a and 7 (or members equivalent for the purpose in view) are adapted 105 to pass through holes 8 provided for the purpose in the walls of the cups adjacent their rims. These bars 6^a and 7 are secured by set screws 9 to the plate 1 to which the cups A are to be fixed, and when these 110

screws 9 are screwed up they cause the cups to be clamped tightly within their respective grooves.

It will be seen that the major sector of 5 the cups is open and unobstructed while the minor sector is covered by the mounting plate or frame (see Figure 3) and that the cups or shells mounted in the above manner are adapted to be stationary.

10 The electrical connection of the cups for the purposes required is effected by means of terminal 10, insulated line 11, screw stud 11^a and external terminal 12.

Upon the plate or frame 1, or adjacent 15 thereto, suitable insulated bearings 14, 14^a, are provided for a brass spindle or shaft 15 and located so that the axis of the spindle corresponds or coincides with the common axis of the cups which lies parallel to the 20 edge of the mounting plate or frame 1. The bearings 14, 14^a, are located each on the outer side of the largest (2) of the fixed cups A and support the spindle 15 so that it may be rotated therein freely but without any 25 play. The spindle 15 is provided, between the two bearings 14, 14^a, with a flattened surface or cut away portion so that a flat surface 16 is provided, which when turned towards the cups A lies substantially in the 30 same plane as that of their rims. This surface extends along the spindle a little farther in each direction than the circumference of the largest or outside cup. Upon this flattened surface 16 grooves are formed and 35 adapted to receive a second series B of hemispherical cups (numbered 2^a to 5^a), corresponding to the set A. This second series of cups B is adapted to alternate with the stationary cups A in such a manner that 40 when in position between these cups they lie without touching them, dividing the air space in accordance with the established practice (see Figures 2 and 4). The grooves 17 are so disposed and the second series of 45 cups so mounted, with half the rim of each cup lying upon each side of the axis of the spindle, that each cup on the spindle is adapted to pass between a pair of the fixed cups and lie in the air space to which reference has already been made. In order to 50 secure the cups B within their respective grooves 17 upon the spindle 15, a bar or rod 18 is provided. The cups A are each formed with an orifice, near their rims and adjacent the axis, through which the bar or rod 18 is passed. Set screws 19 are provided 55 which engage the rod or bar 18 and draw it towards the spindle 15 whereby the cups B are clamped into their grooves 17.

60 A suitable terminal 20 is provided and connected with the spindle 15 by a coiled lead 21 located between two insulated discs 22. This lead 21 establishes a contact with the spindle 15 while at the same time permitting the required rotation of the said 65

spindle. The terminal 20 connects with the external terminal 13.

In order to accommodate the mounting of the spindle in the necessary position, and the mounting of the cups A and B by the 70 aid of bars above referred to, the fixed series of cups A are mutilated or cut away at the extremities of their diameters (as at 23) and the moving cups have portions of their rims cut away (as at 24) to accommodate 75 the mounting bars supporting the fixed cups A.

Around the upper end of the spindle 15 a head piece 25 of suitable material is provided to which is connected by screw thread 80 means, a box or container 26 adapted to enclose the operative part of the apparatus. Upon an extension 27 a disc 28 is mounted and marked with a suitable scale 29. For the purpose of manipulating the condenser 85 a milled head 30 is secured to the extension 27 whereby the spindle 15 may be rotated.

In operation it will be appreciated that upon rotating the spindle 15 the series of (say, negative) cups B mounted thereon 90 will move or revolve relatively to the fixed cups A and will occupy or take up any desired position in reference thereto—according to the capacity which it is desired the condenser should for the moment possess—intermediate the position in which the moving and fixed cups lie entirely within one another (Figures 2 and 3)—with their peripheries or rims in the same plane—and that position—the zero position—in which the series are entirely free of one another in which position the moving and fixed hemispheres together present substantially the appearance of a sphere (Figure 1, dotted position). 100

In Figure 4, it will be observed that the cups B have received a partial rotation through 90° so that the effective areas of the condenser is 50% of the full capacity.

Having now described my invention what 110 I claim as new and desire to secure by Letters Patent is:—

1. A variable electrical condenser comprising a plurality of condenser surface elements each in the form of a cup or shell 115 such as is generated by the partial revolution about an axis of a line which cuts the axis at two points, and means for supporting said condenser surface elements coaxially so that relative rotary movement 120 may be effected between the elements for the purpose of varying their effective or facing area to vary the capacity of the condenser.

2. A variable electrical condenser comprising condenser surface elements of graduated size, each of which is in the form of a cup or shell such as is generated by the partial revolution about an axis of a line which cuts the axis at two points, ar- 130

ranged in two sets, the elements of each set being fixed in relation to one another and nested together so that a space is provided between the elements whereby each 5 series of elements may be introduced into the spaces of the other series upon relative rotary movement taking place.

3. A variable electrical condenser comprising a plurality of condenser surface elements each in the form of a cup or shell such as is generated by the partial revolution about an axis of a line which cuts the axis at two points, means for fixedly and coaxially supporting certain of the condenser 10 surface elements, means for rotatably supporting certain other of the condenser surface elements about the same axis as that about which the fixed elements are mounted whereby the rotatably mounted condenser 15 elements can be rotated relatively to other elements for the purpose of varying the effective or facing area of the condenser elements to vary the capacity of the condenser and means for connecting certain of the elements negatively and the other elements 20 positively in an electric circuit.

4. A variable electrical condenser, comprising condenser surface elements of graduated size, each of which is in the form 25 of a cup or shell such as is generated by the partial revolution about an axis of a line which cuts the axis at two points, arranged in two sets, the elements of each set being fixed in relation to one another and nested 30 together so that a space is provided between the elements whereby each series of elements may be introduced into the spaces of the other series upon relative rotary movement taking place, and means for connecting one set of elements negatively and the other set positively in an electric circuit.

5. A variable electrical condenser comprising a plurality of condenser surface elements each in the form of a semi-spherical cup, means for supporting said condenser surface elements co-axially so that relative rotary movement may be effected between the elements for the purpose of 45 varying the effective or facing area of the condenser to vary the capacity of the condenser, and means for connecting certain of the elements negatively and the other elements 50 positively in an electric circuit.

55. 6. A variable electrical condenser comprising two sets of condenser surface elements of graduated size, each element being in the form of a semi-spherical cup, the elements of each set being fixed in relation to one another and nested together 60 so that a space is provided between the elements, a rotatable spindle having grooves formed therein in which the elements of one set are mounted, a frame member having grooves formed therein in which the elements of the other set are mounted, bar members adapted to pass through orifices in 65

set of elements positively and the other set negatively in an electric circuit.

7. A variable electrical condenser comprising two sets of condenser surface elements of graduated size, each element being 70 in the form of a cup or shell such as is generated by the partial revolution about an axis of a line which cuts the axis at two points, the elements of each set being fixed in relation to one another and nested together 75 so that a space is provided between the elements, a rotatable spindle carrying one set of elements and connected to a terminal of one polarity, a stationary frame member carrying the other set and connected to the terminal of opposite polarity, the movable set of elements being so situated in respect to the other set that upon rotation of the spindle the elements carried by the latter can be caused to move in the spaces of 80 the stationary set for the purpose of varying the effective or facing area of the two sets of elements.

8. A variable electrical condenser comprising two sets of condenser surface elements of graduated size, each element being 85 in the form of a cup or shell such as is generated by the partial revolution about an axis of a line which cuts the axis at two points, the elements of each set being fixed 90 in relation to one another and nested together so that a space is provided between the elements, a rotatable spindle having grooves formed therein in which the elements of one set are mounted, clamping means for securing the said elements in said 95 grooves, the spindle being connected to a terminal of one polarity, a stationary frame member having grooves formed therein in which the elements of the other set are 100 mounted, clamping means for securing these elements in their grooves, said frame member being connected to the terminal of opposite polarity, the movable set of elements being so situated in respect to the other set that upon rotation of the spindle the elements carried by the latter can be caused to move in the spaces of the stationary set for the purpose of varying the effective or facing 105 area of the two sets of elements.

9. A variable electrical condenser comprising two sets of condenser surface elements of graduated size, each element being in the form of a cup or shell such as is generated by the partial revolution about an axis of a line which cuts the axis at two points, the elements of each set being fixed in relation to one another and nested together 110 so that a space is provided between the elements, a rotatable spindle having grooves formed therein in which the elements of one set are mounted, a frame member having grooves formed therein in which the elements of the other set are mounted, bar members adapted to pass through orifices in 115

the elements of each set and secured to the support of the elements as by screw-threaded means, said spindle and frame member being connected, one positively and the other 5 negatively, in an electric circuit, the movable set of elements being so situated in respect to the other set that upon rotation of the spindle the elements carried by the latter can be

caused to move in the spaces of the stationary set for the purpose of varying the effective or facing area of the two sets of elements. 10

In testimony whereof I have signed my name to this specification.

FREDERICK GEORGE GOLDSTONE.
